UNITED STATES PATENT OFFICE.

JOHN REID, OF LONDON, ENGLAND.

FURNACE FRONT.

Application filed June 6, 1921. Serial No. 475,385.

To all whom it may concern:

Be it known that I, JOHN REID, a subject of the King of Great Britain and Ireland, residing at London, England, have invented

5 Improvements in Furnace Fronts, of which the following is a specification.

This invention has reference to furnace fronts, more especially forced draught furnace fronts for steam boilers, objects being 10 to facilitate the free and smooth flow of air into the furnace, especially where centre and wing furnaces are employed as in boilers of the Scotch marine type, to enable the distribution of air to be regulated more satisfactorily to suit varying requirements and to provide simple constructions of furnace fronts suitable for coal burning but convertible for the purpose of oil burning and capable of having parts most liable to be 15 damaged readily replaced from stock or removed, repaired and replaced.

The furnace front, as is usual comprises front and back plates with intermediate ashpit flare and fuel passage casing, an air 20 casing over the fuel passage casing and a sill under it, the pocket or space between the plates around the air casing being in communication with the air supply. Each 25 downwardly extending side of the air casing is in the same plane as the corresponding upwardly extending side portion of the ashpit flare, and the gaps between the sides of the air casing and the flare are occupied by pivoted valves each of which is 30 common to the space between the sill and the ashpit flare and to the space within the air casing around and over the fuel passage casing and controls the flow of air to the 35 said air spaces; the lower edges of the sides 40 of the fuel passage casing are provided with curved extensions which serve to guide or deflect air up the sides and over the top of the fuel passage casing whence it passes through ports into the fuel passage casing 45 and into the furnace. The common valves are preferably so arranged that, in addition to serving to regulate the amount of air simultaneously flowing to the air spaces above and below the sill level, they can be 50 set to admit some air to the space around and over the fuel passage casing, and to regulate the amount thus admitted, without correspondingly opening the space between the sill and the ashpit flare to the air supply. Furthermore, to enable the amount of 55 air passing to the space around and over the

fuel passage casing to be varied to suit the requirements of any particular case, the curved air guiding or deflecting extensions are adapted to be adjusted vertically in relation to the openings controlled by the valves, whilst, to enable the amount of air flowing through the ports in the crown of the fuel passage casing to be varied to suit the conditions of oil firing or coal firing, 60 the said ports are adjustable in size by the insertion or removal of filling pieces or plates.

The accompanying drawings illustrate by way of example a furnace front embodying 70 the present improvements and designed more especially to permit of ready conversion for burning oil or coal.

Fig. 1 being a front elevation;

Figs. 2 and 3 vertical sections at right 75 angles, Fig. 2 being taken on the line 2—2 Fig. 1 and Fig. 3 on the line 3—3 Fig. 2;

Figs. 4 and 5 detail sectional views on the lines C—C and D—D Fig. 3 and Fig. 6 a detail sectional view hereinafter referred to. 80

Fig. 7 is a detail view corresponding to the right hand side of Fig. 3 illustrating a modified arrangement of valve.

Referring to Figs. 1 to 6, the front comprises a front plate *a* and a back plate *b* each formed with projections which, when the two parts are connected by the bolts *a*¹, form the ashpit flare *c*, the fuel passage casing *d* and the air casing *e* thereover; the fuel passage casing *d* is approximately semi-circular in section as regards its upper part, which form is more suitable for fitting an oil burner and its appurtenances after removal of the fire door *i* and the sill *n*, than the usual firebox of approximately rectangular section. Vertical side portions of the flare *c* and the air casing *e* are shown lying in the same planes, and the valves *f* controlling the spaces between them are pivoted at *f*^x and have their upper portions 90 *f*¹ bent outwardly into a different radial plane; each extension *c*^x of the flare *c* is curved to a radius struck from the corresponding pivot *f*^x, the arrangement being such that the valves can be shifted from the intermediate position shown in full lines 100 and in which position air is admitted to the air casing only, to either of the extreme positions indicated by dotted lines, in one of which positions air will be shut off from both the air casing and the ash pit space 105 and in the other position air will be admit-

ted to both. The same result may be obtained without the use of bent valves, by pivoting flat valves so that, when closed, their upper and lower edges abut against the lower edges of the downwardly extending side portions of the air casing *e* and the outer portions of the curved extensions *c* of the flare respectively as shown in Fig. 7. Where the advantage of being able to admit air to the air casing *e* without admitting air to the ashpit is not required, the valves may be flat and when closed lie in the plane of the vertical parts of the air casing *e* and flare *c*. The curved air guiding or deflecting extensions *d* may be cast integral with the projections forming the fire box, but preferably are separate therefrom and adjustably attached thereto in any convenient manner. In one arrangement, as shown in Fig. 6, each extension piece may be formed with a vertical lug *d*¹ adapted to enter somewhat elongated slots in the faces of the said projections and to be frictionally held in the required vertical position when the front and back plates of the front are bolted together.

The crown of the fuel passage casing *d* is formed with ports *h* having recessed edges towards the back plate to receive filling pieces *h*¹ (Figs. 4 and 5) when coal firing, the insertion of the filling pieces concentrating the air supply in front of the door baffle *j* (Fig. 2). The door *i* and the door opening in the front plate *a* are of usual standard rectangular shape so that when the door is open, the ports *h* are rendered accessible for fitting in the filling pieces *h*¹. But instead of the fuel passage casing *d* being formed by projections on the front and back plates as shown, it may be of the withdrawal type to enable the filling pieces to be more easily fitted.

The spindles of the valves *f* are provided with handles *o* which constitute means for setting the valves and have locking arms which are adapted to engage the corresponding corners of the closed fire door independently for the purpose of preventing it being opened whilst the valves are set to admit air to the ashpit space.

In some cases the top of the air casing may be formed with a central port which may be closed by a valve or removable plate when required.

The drawings illustrate a front arranged for coal firing but it will be understood that to adapt the front for oil burning the fire door is replaced by a suitable closure carrying the required oil burning devices, the sill is removed and the filling pieces are removed from the ports in the crown of the firebox.

What I claim is:—

1. A furnace front comprising front and back plates, intermediate ashpit flare, fuel

passage casing, air casing thereover, a removable sill, openings between the air casing sides and the flare, pivoted valves controlling said openings, each of which valves is common to the air space between the sill and the flare and the air space within the air casing, outwardly turned extensions on the fuel passage casing projecting towards the valve pivots and means for setting said valves so as to open said air spaces to the air supply. 70 75

2. A furnace front comprising front and back plates, intermediate ashpit flare, fuel passage casing, air casing thereover, a removable sill, openings between the air casing sides and the flare, pivoted valves controlling said openings, each of which valves is common to the air space between the sill and the flare and the air space within the air casing, and is adapted to be set so as to open the space within the air casing to the air supply without correspondingly opening the space between the sill and the flare. 80 85

3. A furnace front comprising front and back plates, intermediate ashpit flare, fuel passage casing, air casing thereover, a removable sill, openings between the air casing sides and the flare, pivoted valves controlling said openings, each of which valves is common to the air space between the sill and the flare and the air space within the air casing, the upper part of each valve closing against the edge of the air casing side and the lower part of each valve moving over a curved extension of the flare. 90 95 100

4. A furnace front comprising front and back plates, intermediate ashpit flare, fuel passage casing, air casing thereover, a removable sill, openings between the air casing sides and the flare, pivoted valves controlling said openings, each of which valves is common to the air space between the sill and the flare and the air space within the air casing, the upper part of each valve closing against the edge of the air casing side and the lower part of each valve moving over a curved extension of the flare and each valve having upper and lower parts in different radial planes. 105 110 115

5. A furnace front comprising front and back plates, intermediate ashpit flare, fuel passage casing, air casing thereover, a removable sill, openings between the air casing sides and the flare, pivoted valves controlling said openings, each of which valves is common to the air space between the sill and the flare and the air space within the air casing, a fire door for closing the front of the fuel passage casing, means for setting said valves so as to open the said air spaces to the air supply and means adapted to then interlock each valve independently with the fire door. 120 125 130

6. A furnace front comprising front and

- back plates, intermediate ashpit flare, fuel passage casing, air casing thereover, a removable sill, openings between the air casing sides and the flare, pivoted valves controlling said openings, each of which valves is common to the air space between the sill and the flare and the air space within the air casing, the upper part of each valve closing against the edge of the air casing side and the lower part of each valve moving over a curved extension of the flare, a fire door for closing the front of the fuel passage casing, means for setting said valves so as to open the said air spaces to the air supply and means adapted to then interlock each valve independently with the fire door.
7. A furnace front comprising front and back plates, intermediate ashpit flare, fuel passage casing, air casing thereover, a removable sill, openings between the air casing sides and the flare, pivoted valves controlling said openings, each of which valves is common to the air space between the sill and the flare and the air space within the air casing a fire door for closing the front of the fuel passage casing, an internal baffle attached thereto, air ports in the fuel passage casing through which air can pass between the door and baffle, and means for setting the valves so as to allow air to pass to the air casing and through said ports and to the space between the sill and the ashpit flare.
8. A furnace front comprising front and back plates, intermediate ashpit flare, fuel passage casing, air casing thereover, a removable sill, openings between the air casing sides and the flare, pivoted valves controlling said openings, each of which valves is common to the air space between the sill and the flare and the air space within the air casing, outwardly turned, extensions on the

fuel passage casing projecting towards the valve pivots said extensions being adjustable vertically, and means for setting said valves so as to open said air spaces to the air supply.

9. A furnace front comprising front and back plates, intermediate ashpit flare, fuel passage casing, air casing thereover, a removable sill, openings between the air casing sides and the flare, pivoted valves controlling said openings, each of which valves is common to the air space between the sill and the flare and the air space within the air casing, a fire door for closing the front of the fuel passage casing, an internal baffle attached thereto, air ports in the fuel passage casing through which air can pass between the door and baffle, removable filling pieces partly closing said ports, and means for setting the valves so as to allow air to pass to the air casing and through said ports and to the space between the sill and the ashpit flare.

10. A furnace front comprising front and back plates, intermediate ashpit flare, fuel passage casing of semi-circular section, air casing thereover, a removable sill, openings between the air casing sides and the flare pivoted valves controlling said openings, each of which is common to the air space between the sill and the flare and the air space within the air casing, a rectangular fire door closing the front of the fuel passage casing, air ports in the fuel passage casing through which air can pass, and means for setting the valves so as to allow air to pass to the air casing and through said ports and to the space between the sill and the ashpit flare.

Signed at London, England, this 12th day of May, 1921.

JOHN REID.
